UNITED STATES PATENT OFFICE.

ANDERS H. NESHEIM, OF MILWAUKEE, WISCONSIN, ASSIGNOR, BY MESNE ASSIGNMENTS, TO FEDERAL STEEL SASH COMPANY, OF WAUKESHA, WISCONSIN, A CORPORATION OF WISCONSIN.

WINDOW.

Application filed December 12, 1921. Serial No. 521,737.

To all whom it may concern:

Be it known that I, ANDERS H. NESHEIM, a citizen of the United States, and resident of Milwaukee, in the county of Milwaukee, and State of Wisconsin, have invented new and useful Improvements in Windows, of which the following is a description, reference being had to the accompanying drawings, which are a part of this specification.

10 This invention relates to improvements in windows, particularly to that type of window wherein the sash frame is pivotally mounted at its top to the window frame and adapted to be swung either inwardly or outwardly, for example, like a storm window or a basement window.

One of the objects of the invention is to provide novel means for pivotally mounting the sash frame on the window frame of such construction that none of the ordinary hinges or pivotal connections commonly used need be employed.

In its preferred form the invention contemplates a window frame having a top member and a sill member which are connected by vertically extending side members; and a more specific object of the invention is to provide flanges on said side members which are provided adjacent the top member with horizontally disposed shoulders, in combination with a sash frame having out-turned flanges adapted to overlap the respective flanges on said side members, the out-turned flanges being provided with backwardly and horizontally extending portions adapted to rest on said shoulders so that the sash frame will be pivotally mounted with respect to the window frame.

A further object of the invention is to provide a sash frame having Z-shaped members at its sides and bottom, the members at the sides being disposed so that out-turned flanges are provided to overlap the flanges on the window frame, the bottom member of the sash frame being disposed so as to provide a depending flange adapted to overlap the sill member of the window frame thereby providing a weather-proof construction at the sides and bottom of the sash frame.

The invention consists in the novel constructions and arrangements to be hereinafter described and claimed for carrying out the above stated objects and such other ob-

jects as will appear from the following description of a certain preferred embodiment illustrated in the accompanying drawings, wherein—

Fig. 1 is an elevational view of a window embodying the principles of the invention, the sash being in its closed position;

Fig. 2 is a sectional view taken on the line 2—2 of Fig. 1;

Fig. 3 is a sectional view, on an enlarged scale, taken on the line 3—3 of Fig. 1;

Fig. 4 is a sectional view taken on the line 4—4 of Fig. 3; and

Figs. 5 and 6 are sectional views, on an enlarged scale, taken on the lines 5—5 and 6—6, respectively, of Fig. 1.

Like characters of reference designate like parts in the several views.

Referring now to the drawings, the window frame includes a horizontally extending inverted channel member 8 at the top and a similarly extending inverted channel sill member 9 at the bottom, said sill member preferably being formed of angle irons 9^a and 9^b, the horizontal flanges of which overlap, as clearly shown in Figs. 2 and 6, and are welded together. Vertically extending side members 10 are connected at their upper ends to the top member 8 and at their lower ends to the sill member 9. The side members 10 include an F-shaped bar 11 having a flange portion 11^a and a flat portion 11^b welded thereto, see particularly Fig. 5.

The sash frame is provided at its top with a horizontally extending angle bar 12 disposed so as to provide a horizontal flange 12^a and a depending vertical flange 12^b. The sides of the sash frame include an angle bar 13 having a flange 13^a and a flange 13^b, and also an angle bar 14 having a flange 14^a and a flange 14^b, said flanges 13^b and 14^b being welded together, thus providing substantially Z-shaped members at the sides of the sash frame. The bottom of the sash frame includes an angle bar 15 having a vertical flange 15^a and a horizontal flange 15^b, also an angle bar 16 having a vertical depending flange 16^a and a horizontal flange 16^b, said flanges 15^b and 16^b being welded together thereby providing at the bottom of the sash frame a member of substantially Z-shape. In the embodiment herein shown the sash frame is provided with a vertically extend-

ing center member 17. Panes of glass 18 are disposed against the flange 12^b of the angle bar 12, the flange 15^a of the angle bar 15, the flange 13^a of the angle bar 13 and against 5 a suitable flange (not shown) provided on the center member 17, being held thereagainst by any suitable means, for example, putty 19.

It will now be apparent, when the sash 10 frame is in the position shown in Fig. 1, that the flanges 14^a of the Z-shaped side member of the sash frame will overlap the flange 11^a of the respective side window frame members 11, as clearly shown in Fig. 15, also that the depending flange 16^a of the Z-shaped bottom member of the sash frame will overlap the vertically disposed flange of the angle bar 9^b which forms a portion of the sill member. In order to pivotally support 20 the sash frame on the window frame, the flanges 11^a of the angle bars 11 are formed adjacent their upper ends with horizontally disposed shoulders 20, and the upper ends of the flanges 14^a are bent backwardly to provide 25 substantially horizontally extending portions 21, see Figs. 3 and 4, which are adapted to rest upon the shoulders 20. As clearly shown in Figs. 3 and 4, the angle bar 12 extends to each side of the sash frame sufficiently so 30 that the extremities of the flange 12^a thereof overlap and rest upon the horizontal portions 21 and are welded thereto thereby providing a rigid and strongly reinforced construction at the upper corners of the sash 35 frame. Wear plates 22 are preferably disposed underneath the respective horizontal portions 21, being welded thereto so that the horizontal portion 21 will not be weakened by wearing away by reason of the swinging 40 of the sash frame on the shoulders 20. The flanges 11^b of the angle bars 11 are cut away at their upper ends, as 23, see Fig. 4, sufficiently to provide room for the laterally extending flanges 12^b when the sash frame is 45 swung from its closed position to its open position substantially as shown in dotted lines in Fig. 3, and vice versa. If desired, vertically extending strips 24 secured at their upper ends to the channel member 8 50 and at their lower ends to the sill member 9 may be provided against which the outer sides of the flanges 13^a of the sash side members may abut when the sash frame is in its closed position, in that event the members 24 are bent outwardly at their upper 55 ends, as clearly shown in Figs. 2 and 3, to provide for swinging of the sash frame. The sash frame may be locked in its closed position in any desired manner, for example, by a latching member 25 pivoted on the sash frame and adapted to engage behind a suitable keeper 26 fixed to the sill member 9 of the window frame.

It will be apparent from the foregoing description 60 that a window constructed accord-

ing to this invention will be inexpensive to manufacture, strong and durable and one in which the sash frame may be freely swung relative to the window frame without the use of any special hinges or pivotal connections. 70

I claim:

1. In combination a frame having at its sides vertically extending flanges which are formed adjacent the top of the frame with aligned horizontally disposed shoulders, and a sash frame having vertically extending out-turned flanges at its sides which overlap the respective first mentioned flanges, said last mentioned flanges being provided with 75 backwardly and horizontally extending portions adapted to bear on said respective shoulders, for the purpose specified. 80

2. In combination a frame having a top member, a sill member, and at its sides vertically extending members connected to said top and sill members and being provided with flanges, said flanges being formed adjacent said top member with aligned horizontally disposed shoulders, and a sash frame having at its sides out-turned flanges which overlap the respective first mentioned flanges and at its bottom a depending flange adapted to overlap said sill member, said 85 out-turned flanges being provided with 90 backwardly and horizontally extending portions adapted to bear on said respective shoulders, for the purpose specified. 95

3. In combination a frame having a top member, a sill member, and at its sides vertically extending members connected to said top and sill members and being provided with flanges, said flanges being formed adjacent said top member with aligned horizontally disposed shoulders, and a sash 100 frame having at its sides and bottom Z-shaped members disposed so that out-turned flanges are provided at the respective sides of said sash frame adapted to overlap said first mentioned flanges and a depending flange is provided at the bottom of said sash frame adapted to overlap said sill member, said out-turned flanges being provided with 105 backwardly and horizontally extending 110 portions adapted to bear on said respective shoulders, for the purpose specified. 115

4. In combination a frame having at its sides vertically extending flanges which are formed adjacent the top of the frame with aligned horizontally disposed shoulders, and a sash frame having at its top a horizontally extending member the extremities of which project beyond the sash frame proper and at its sides vertically extending out-turned flanges which overlap the respective first mentioned flanges, said out-turned flanges at their upper ends being bent backwardly to provide portions adapted to bear 120 on said respective shoulders, said portions 125

being fastened to the respective extremities of said horizontally extending member, for the purpose specified.

5. In combination a frame having at its sides vertically extending flanges which are formed adjacent the top of the frame with aligned horizontally disposed shoulders, a sash frame having at its top a horizontally extending member the extremities of which project beyond the sash frame proper and at its sides vertically extending out-turned flanges which overlap the respective first mentioned flanges, said out-turned flanges at their upper ends being bent backwardly to provide horizontal portions disposed over said respective shoulders, said portions being fastened to the respective extremities of said horizontally extending member, and wear plates fastened to the under sides of said respective horizontal portions, for the purpose specified.

6. In combination a window frame including side members provided adjacent the top with aligned horizontally disposed

shoulders, and a sash frame having vertically extending out-turned flanges, said flanges being provided with backwardly and horizontally extending portions adapted to bear on said respective shoulders, for the purpose specified. 25
30

7. In combination a window frame including side members provided adjacent the top with aligned horizontally disposed shoulders, and a sash frame having at its top a horizontally extending member the extremities of which project beyond the sash frame proper and at its sides vertically extending out-turned flanges which overlap the respective first mentioned flanges, said out-turned flanges at their upper ends being bent backwardly to provide portions adapted to bear on said respective shoulders, said portions being fastened to the respective extremities of said horizontally extending member, for the purpose specified. 35
